UNITED STATES PATENT OFFICE.

JOSEPH KRUPKA, OF COALRIDGE, OHIO.

ORDNANCE AND ADJUSTABLE CARRIAGE THEREFOR.

1,249,778.

Specification of Letters Patent. Patented Dec. 11, 1917.

Application filed May 12, 1917. Serial No. 168,105.

To all whom it may concern:

Be it known that I, JOSEPH KRUPKA, a subject of the Emperor of Austria, residing at Coalridge, in the county of Noble and State of Ohio, have invented certain new and useful Improvements in Ordnance and Adjustable Carriages Therefor, of which the following is a specification.

This invention relates to certain new and useful improvements in ordnance and adjustable carriage therefor.

The primary object of the invention is the provision of a mounted field piece cannon adapted to be readily elevated and automatically lowered when desired after the nature of a disappearing carriage, provision being made for counterbalancing the movable portion of the device, while the cannon is adapted to be revolved at any level that is found desirable.

A further object of the invention is the provision of a cannon, or field piece especially adapted for use in coast defense where the loading of the gun at a point without the line of vision of the enemy is desirable.

A still further object of the device is the provision of a disappearing gun carriage adapted to be manually operated and provided with counterbalancing means rendering the raising of the carriage an easy matter as well as cushioning and rendering gradual the downward movement of the carriage, releasable means being arranged for adjustably maintaining the carriage at any desired elevation, and possessing sufficient rigidity for firing purposes.

In the drawings forming a part of this application, like designating characters refer to corresponding parts throughout the several views.

Figure 1, is a side elevation of the device in its elevated position, a portion of the railing being broken away.

Fig. 2 is a top plan view thereof.

Fig. 3 is an enlarged side elevation of a portion of the device.

Fig. 4 is an enlarged detail sectional view taken upon line IV—IV of Fig. 3.

Fig. 5 is a horizontal sectional view taken upon line V—V of Fig. 1.

Fig. 6 is an enlarged detail sectional view taken upon line VI—VI of Fig. 2.

Fig. 7 is an enlarged view of the lower

portion of one of the adjustable mounting legs, and,

Fig. 8 is a sectional view of a beveled gear employed with the device.

Referring more in detail to the drawings, it will be understood that the present form of gun and the disappearing carriage therefor may be employed at any desired point, the same being herein illustrated mounted upon a rectangular platform 10 provided with an encircling rail 11 positioned therearound at a desired elevation, the platform 10 being supported by corner posts 12.

A gun carriage 13 is arranged with side plates 14 having a cannon 15 tiltably mounted upon the upper ends thereof and arranged to revolve upon a substantially rectangular main base 16 arranged parallel with the platform 10. A housing 17 is mounted beneath the main base 16 having a guide post 18, rectangular in cross-section carried centrally by a sub-base 16' attached by struts 61 to the carriage 13, the said sub-base being revolvably in contact with the lower face of the base 16, the said post 18 being slidably arranged through the said housing. A beveled gear 19 is horizontally journaled within a ring 20 carried by the platform 10 centrally within the housing 17, a retaining screw 21 extending through the ring 20 with its inner end freely positioned within an annular slot 22 of the gear 19 while the post 18 freely projects through a central rectangular opening 23 in the said gear and through a rectangular opening 24 in alignment therewith provided in the platform 10.

A stub-shaft 25 is journaled through the side 26 of the housing 17 carrying a pinion 27 in constant mesh with the gear 19, a turn crank 28 being provided for the said shaft 25. By this arrangement it will be understood that upon turning the gear 19 by means of the crank 28, the post 18 will be revolved, thereby revolving the carriage 13 which is mounted by means of wheels 29 upon a circular track 30 carried by the base 16. By reason of the sliding movement of the post 18 through the gear 19 and the platform 10 it will be evident that the carriage 13 may be revolved in either direction desired regardless of its horizontal adjustment or its height above the platform 16.

The gun 15 being attached to an axle 31 journaled in the upper ends of the members 14, the same is arranged with a gear 32 engaged by a worm 33 operable by a crank 34 for the purpose of suitably tilting the gun in either direction for sighting the same. A drum 35 is provided at one end of the axle 31 arranged with a strap-brake 36 tightened by means of a bolt member 37 whereby the gun 15 may be retained at any desired inclination. A semicircular arm 38 depends from the gun 15 and extends between the members 14 in engagement with a pinion 39 arranged therein and provided with an operating crank 40 at its outer end whereby the tilting of the cannon is more perfectly controlled and may be steadied. It will be evident that the gun 15 may be of any desired form, the same being herein shown provided 20 with a breech loading device 41. A supporting leg 42 is pivoted to the base 16 at each corner thereof as at 43 and is provided with spaced wheels 44 at its lower end, spanning a toothed rack 45 carried by the platform 10 and diagonally positioned with respect thereto. A gravity pawl 46 is pivoted to each of the legs 42 adjacent the wheels 44 thereof for engaging the adjacent rack 45, it being evident that an elevation of the base 16 draws the lower ends of the legs 42 inwardly toward the corners of the housing 17, said lower ends of the legs traveling upon the wheels 44 and the pawls 46 ratcheting over the racks 45, thereby maintaining the base 16 in its adjusted elevated position supported by the said legs 42. Depending racks 47 are attached at opposite points of the base 16 extending through 30 slots 48 in the platform 10, the said racks 47 being arranged adjacent the opposite sides of the housing 17 in contact with suitable rollers 49 carried by the sides of the said housing. Gears 50 journaled upon the outer ends of a shaft 51 extending through the housing 17 are in constant mesh with the racks 47, while a turn-crank 52 is provided upon one end of the shaft 51. It will be understood that by turning the crank 50 55 in the required direction, the racks 47 will be elevated thereby raising the base 16 while the legs 42 will support the base 16 at the desired elevation. Arcuate platforms 53 are mounted upon the legs 42 outwardly of the base 16. Counterbalancing weights 54 are connected to the base 16 by means of cables 55 passing over pulleys 56 suitably arranged above the platform 10, a releasing cord 57 being attached to each of the pawls 46 and to a separate spool 58 mounted upon a shaft 59 journaled through the base 16. When the carriage 13 is elevated and it is desired to lower the same, one of the cranks 60 carried by the shaft 59 is turned for pulling

the ropes 57 upwardly thereby releasing the pawls 46 and permitting the legs to move outwardly upon the wheels 44 during the lowering of the base 16, the lowering thereof being gradual since it is governed by the weights 54. 70

A serviceable base and carriage is provided for the gun 15 permitting the latter to be easily elevated for firing and then lowered for the purpose of reloading the same, the structure possessing great strength and being readily and quickly operated under service conditions. 75

What I claim as new is: 80

1. A gun support comprising a vertically movable main base, swinging legs carried by said base, adjustable retaining means for the lower ends of the legs and elevating means for the base. 85

2. A gun support comprising a vertically movable base, swinging legs carried by the base, adjustment retaining means for the lower ends of the legs and elevating means for the base, counterbalancing means for the base and releasing means for the adjustment retaining means whereby the base is automatically lowered upon the release thereof. 90

3. A device of the class described comprising a main base, a gun carriage revolvably mounted thereon, elevating means for said base, depending corner legs hinged to the base, pawl and ratchet retaining means at the lower ends of the legs and releasing means for the said retaining means. 95

4. A device of the class described comprising a main base, a gun carriage revolvably mounted thereon, a sub-base beneath the said main base, connections between the said carriage and sub-base whereby the carriage is retained revolvably shiftable upon the said main base, depending legs hinged to the said main base, pawl and ratchet means at the lower ends of the legs, releasing means for the said pawl and ratchet means, and counterbalancing means for the said main base. 100

5. A device of the class described comprising a vertically movable main base, a gun carriage mounted thereon, a support beneath the said base, toothed racks upon the said support, depending legs hinged to the said base, spaced wheels upon the lower ends of the said legs, guidingly arranged over the said racks, and gravity pawls carried by the lower ends of the said legs and in normal engagement with the said racks. 115

6. A device of the class described comprising a vertically movable main base, a gun carriage mounted thereon, a support beneath the said base, toothed racks upon the said support, depending legs hinged to the said base, spaced wheels upon the lower ends of the said legs, guidingly arranged over the said racks, gravity pawls carried by the lower ends of the said legs and in normal engagement with the said racks, and simulta- 120

neously operable releasing means for the said pawls and counterbalancing means for the base adapted for permitting the downward movement of the base and carriage 5 when the pawls are released.

7. A device of the class described comprising a vertically adjustable main base, a carriage revolvably mounted thereon, a gear having a rectangular central opening positioned beneath the main base, a sub-base 10

attached to the carriage, a rectangular post depending from the said sub-base freely arranged through an opening in the said gear, and turning means for the said gear.

In testimony whereof I affix my signature. 11

JOSEPH KRUPKA.
